UNITED STATES PATENT OFFICE.

CHARLES L. BAKER AND JOHN E. KLOS, OF LANCASTER, PENNSYLVANIA.

UMBRELLA-RUNNER.

1,240,645.

Specification of Letters Patent. Patented Sept. 18, 1917.

Application filed May 24, 1915. Serial No. 30,138.

To all whom it may concern:

Be it known that we, CHARLES L. BAKER and JOHN E. KLOS, citizens of the United States, residing at Lancaster, in the county 5 of Lancaster and State of Pennsylvania, have invented certain new and useful Improvements in Umbrella-Runners, of which the following is a specification, reference being had therein to the accompanying drawing.

This invention relates to an improved umbrella runner or spider of the ball and socket type, as shown in United States Patent No. 924,627, granted on June 15, 1909.

In the construction shown and described in the above referred to patent, the curved arms which formed the sockets for the ball of the ribs were apt to open and release the rib.

The present invention overcomes this fault by the novel construction shown which comprises a runner formed from a solid piece which is milled out to receive the ball ends of the ribs.

The object of the invention is to provide a device of this class that shall be cheap, durable and efficient, and be readily adapted to have the ribs removed and renewed singly without removing all of the ribs.

With these and other objects in view, our invention consists in certain construction and combination of parts as will hereinafter be fully described and claimed in the annexed specification, and illustrated in the accompanying drawings, which form a part of this application, and in which like figures of reference refer to corresponding parts in all of the views; but it is fully understood that while we have here described our invention as shown, that we do not confine ourselves to the exact design, as slight changes may be made in the construction and arrangement of the several parts without departing from the spirit of the invention.

Referring to the drawings forming a part of this application:—

Figure 1, is an elevation of a partial view of an umbrella stick, showing the runner and top notch with a single rib and stretcher attached thereto.

Fig. 2, is a bottom view of a rib or stretcher, showing my novel construction of ball end.

Fig. 3, is a side view of the same.

Fig. 4, is a vertical sectional view of my improved runner, taken on the line X—X of Fig. 5, with the ribs removed.

Fig. 5, is a top plan view of the runner.

Fig. 6, is a bottom plan view of the same.

In the drawings, the umbrella-stick or rod is indicated by 1, and the top-notch by 2. This notch is slotted, the same as the runner hereinafter referred to, the slots being denoted by 9. The construction whereby the rib-ends may be inserted is substantially the same as that employed with the runner hereinafter described in detail. A rib, partly broken away and indicated by 3, is shown in connection with the top-notch. The runner is of the form shown in Figs. 1, 4, 5 and 6. It may be said to comprise a tubular member or body portion 4, mounted to slide upon the stick and having near its upper end an outwardly-extending annular rib or flange 5. It is likewise provided with the usual slot 6, for the reception of the locking spring (not shown) mounted upon the stick. Upon the upper end of the runner 4 is mounted the retaining device for the spherical heads upon the lower ends of the stretchers, said member comprising a sleeve 7 formed with an enlarged head 8, preferably rounding in outline, which head is radially milled to form a plurality of slots, as 9, through which the stretchers 10, or the ribs, as the case may be, are passed. The inner ends of said milled slots 9 are counterbored, forming sockets 11 for the reception of the spherical or ball ends 12 of the stretchers. The upper end of the runner 4, extending from the retaining member or element, forms an inner wall for the slots 9 and prevents the ball-ends 12 from passing out of the sockets when once the parts are placed and locked in position.

The lower edge of the sleeve 7 is crimped over the flange or bead 5 to hold the member 7 and slide against relative endwise movement, while still permitting a relative rotative movement of the parts. The upper end of the runner 4 is provided with a slot 13 (Figs. 4 and 5) which may be brought into register with any one of the slots 9 and its socket 11 by turning the sleeve 7 upon the member 4. This will permit the insertion or removal of a rib or stretcher-end, as the case may be, and after the stretcher is inserted a partial relative rotation of the members 4 and 7 will carry the slot 13 out

of alinement with the slot 9 with which it was previously alined and prevent movement of any of the stretcher-ends inwardly.

In order to prevent the sleeve 7 from rotating upon the runner 4, and to retain the parts in their adjusted positions, a tongue 14 is cut from the runner 4, and bent out into a notch, as 15, formed in the lower edge of the member 7.

10 Should a rib or stretcher become broken, and it is desired to replace the parts, the stick 1 is removed, the tongue 14 released from the slot 15, and member 4 revolved in the retaining element 7 until the slot 13 is 15 brought into alinement with the slot 9 through which the broken rib or stretcher extends. The stretcher-end may then be removed by a slight inward movement to free the head 12 from the socket 11, and thereafter giving it a slight upward movement to carry it free of the slot. When this is 20 accomplished the rod or stretcher may be taken out and replaced without loosening or removing the remaining ribs or stretchers.

25 Having thus described our invention, what we claim is:

1. In a runner for umbrellas, the combination of a tubular member provided with a longitudinally-extending slot at its upper 30 end; a sleeve rotatably mounted thereon, said sleeve having an enlarged head provided with a series of slots extending through the upper portion thereof with a socket or recess formed at the inner end of 35 each slot; and means for preventing relative longitudinal movement of said tubular member and the sleeve, while permitting relative rotative movement, whereby any slot in the sleeve may be brought into register 40 with the slot in the tubular member.

2. In a runner for umbrellas, the combination of a tubular member provided with a longitudinally-extending slot at its upper end; a sleeve rotatably mounted thereon, said member having an enlarged head provided with a series of slots extending through the upper portion thereof with a socket or recess formed at the inner end of each slot; and an annular bead formed 45 upon the tubular member and interlocking with the sleeve to prevent separation of said members while permitting relative rotation thereof.

3. In a runner for umbrellas, the combination of a tubular member provided with a longitudinally-extending slot at its upper end; an annular bead formed upon the outer face of the tubular member; a sleeve rotatably mounted on said tubular member; said

60 sleeve having a head provided with a series of radially-disposed slots extending through the upper portion thereof, with a socket or recess formed at the inner end of each slot, the lower end of the sleeve being spun inwardly beneath the bead aforesaid and thereby locking the tubular member and sleeve against separation while permitting relative rotation; and a tongue extending from the tubular member, adapted to enter an opening formed in the sleeve, said tongue serving, when in said opening, to hold the sleeve and tubular member against relative rotation, and with the slot in the tubular member out of line with any of the slots in the head of the sleeve.

65 4. In a runner for umbrellas, the combination of a tubular member provided with a longitudinally-extending slot at its upper end; a sleeve rotatably mounted thereon, said sleeve having a head provided with 70 a series of radially-disposed slots extending through the upper portion thereof with a socket or recess formed at the inner end of each slot; means to prevent longitudinal separation of said members; and a tongue 75 extending from the tubular member and adapted to enter an opening formed in the sleeve, said tongue serving, when in said opening, to hold the sleeve and tubular member against relative rotation, and with the slot in the tubular member out of line with any of the slots in the head of the sleeve.

80 5. In a runner for umbrellas, the combination of a tubular member provided with a longitudinally-extending slot at its upper end; a sleeve rotatably mounted thereon, said sleeve having an enlarged head provided with a series of slots extending through the upper portion thereof with a socket or recess formed at the inner end of 85 each slot; means for preventing relative longitudinal movement of said tubular member and the sleeve, while permitting relative rotative movement, whereby any slot in the sleeve may be brought into register 90 with the slot in the tubular member; and means for normally holding the sleeve against rotative movement, with the slot in the tubular member out of alinement with any of the slots in the sleeve.

95 100 105 110 In testimony whereof, we affix our signatures in presence of two witnesses.
